UNITED STATES PATENT OFFICE.

MARK W. BAILEY, OF NEW YORK, N. Y.

DESIGN FOR A LIQUID-PROJECTING DEVICE.

55,017.

Specification for Design.

Patented May 4, 1920.

Application filed October 13, 1919. Serial No. 330,499. Term of patent 7 years.

To all whom it may concern:

Be it known that I, MARK W. BAILEY, a citizen of the United States, residing at New York, in the county of New York and State of New York, have invented a new, original, and ornamental Design for a Liquid-Projecting Device, of which the following is a specification, reference being had

to the accompanying drawing, forming part thereof.

The figure is a plan view of a liquid projecting device, showing my new design.

I claim:

The ornamental design for a liquid projecting device, as shown.

MARK W. BAILEY.
